UNITED STATES PATENT OFFICE.

LEROY S. BARTLETT AND CLIVE H. BARTLETT, OF ST. LOUIS, MISSOURI.

BOTTLE-CLOSURE.

SPECIFICATION forming part of Letters Patent No. 724,779, dated April 7, 1903.

Application filed December 19, 1902. Serial No. 135,834. (No model.)

To all whom it may concern:

Be it known that we, LEROY S. BARTLETT and CLIVE H. BARTLETT, citizens of the United States, residing in the city of St. Louis, in the 5 State of Missouri, have invented certain new and useful Improvements in Bottle-Closures, of which the following is a full, clear, and exact description, reference being had to the accompanying drawings, forming part of this 10 specification.

Our invention relates to a bottle having a closure of a construction designed to prevent fraudulent refilling thereof without detection.

Our invention consists in features of novelty hereinafter fully described, and pointed 15 out in the claims.

Figure I is a perspective view of our bottle, the parts being shown disassembled. Fig. II is a perspective view of the bottle complete. 20 Fig. III is a cross-section taken on line III III, Fig. II, through the neck of the bottle and its closure. Fig. IV is a vertical section taken on line IV IV, Fig. II.

1 designates a bottle the neck 2 of which 25 terminates in an annular rim 3. The mouth of the bottle is preferably closed by a stopper 4.

5 designates a band of soft material, preferably metal, such as lead or soft alloy, that encircles the neck of the bottle between the bottle-body and the annular rim 3 to be confined 30 beneath said rim.

6 is a cap of thin metal fitted over the neck of the bottle to inclose it and the band 5. The edge of the cap preferably extends slightly beyond the lower edge of the band 5, as seen in 35 Fig. IV, so that an instrument may be slipped thereunder when it is desired to open the bottle. The cap 6 is preferably of tin or other metal, being made of as slight thickness as 40 will resist ordinary usage in the handling of bottles. In the cap 6 we produce a series of indentations 7, whereby prongs of the metal of the cap are embedded at intervals into the soft-metal band 5, as seen most clearly in 45 Figs. III and IV, and the cap is securely held to the neck of the bottle.

When the bottle is to be opened, a suitable instrument is introduced beneath the edge of the cap 6 at any point, and the cap is cut or 50 torn to sever its connection with the soft-metal band 5, when it may be readily removed

and access to the contents of the bottle be obtained on the extraction of the stopper 4. It will be seen that after the bottle has been opened in the manner stated it is impossible 55 for a fraudulent user to again put it into its original condition without being equipped with the destroyed parts of the closure, which would in most instances bear the name of or the symbols of the original user of the bottle, 60 thereby rendering fraudulent use extremely difficult.

We are aware that it is not new to place a band of rubber around the neck of a vessel, such as a jar, and seat a flange-rim of a cover 65 over the mouth of said jar, in which a continuous indentation is formed to produce a bead that extends into said rubber band. Our invention differs from such construction in that we utilize soft metal instead of rubber 70 as a material for the band applied to the vessel and by indenting the cover of cap inclosing said band form prongs which embed into said metal and provide a holding means much more efficient than can be obtained by the 75 production of a plain bead embedded continuously into the band. By utilizing soft metal as a material for the band we have the advantage of a material that will not deteriorate or disintegrate in service, as will rubber 80 when used for the same purpose and also a material that is not subject to being acted upon deleteriously by acids or other substances likely to cause deterioration of the band, as is rubber. 85

We claim as our invention—

1. The combination with a bottle body and neck, of a band of soft metal applied to said neck, and a cap fitted over said neck and band and indented at intervals into said band, 90 substantially as set forth.

2. The combination with a bottle body and neck provided with a rim, of a band of soft metal applied to said neck, and a cap fitted over said neck and band and indented at intervals into said band, substantially as set 95 forth.

LEROY S. BARTLETT.
CLIVE H. BARTLETT.

In presence of—

E. S. KNIGHT,
M. P. SMITH.
